UNITED STATES PATENT OFFICE

AUGUST MITCHELL, OF NEW YORK, N. Y., ASSIGNOR TO SCOVILL MANUFACTURING COMPANY, OF WATERBURY, CONNECTICUT, A CORPORATION OF CONNECTICUT

CAP FOR JARS AND THE LIKE

Application filed April 18, 1930. Serial No. 445,246.

This invention relates to certain improvements in caps for jars and the like which are provided with an open mouth.

Jars and the like, particularly glass jars, 5 largely used for packaging fruits, cosmetics and the like are provided with an open mouth through which the contents of the jar may be removed. It is desirable to provide these jars with a closure cap which may be readily and 10 easily applied to the jar and locked in rigid relation therewith, but at the same time may be readily removed therefrom. For economy in manufacture, it is further desirable that these caps be of as few parts as possible and 15 that the locking means be of simple character so that the caps can be cheaply made and assembled, and will be sufficiently rigid and strong to adapt them for the use for which they are intended. It is furthermore desir- 20 able that the means by which the caps are secured to the jars shall be concealed so as to make a neat and attractive package.

It is the especial object of the present invention to produce a two part cap for glass 25 jars and the like which is provided with a locking shoulder in which the parts of the cap are provided with concealed means for locking them together, and in which the locking means by which the cap is secured in position on the jar is also concealed.

A further object of the invention is to produce such a cap the parts of which can be formed of drawn metal so that the cap can be cheaply produced and assembled, thus pro- 30 viding an economical structure.

A cap embodying the invention in its preferred form is shown in the accompanying drawing, in which

Figure 1 is a side view of the improved 40 cap applied to an open mouth container, such as a jar, the latter being shown in dotted lines;

Figure 2 is a top view of the cap shown in 45 Figure 1;

Figure 3 is an inside view of the cap of Figure 2;

Figure 4 is a sectional view, drawn on an enlarged scale, of the cap of Figure 3, the section being taken on line 4—4 of that figure, 50 and

Figure 5 is a detail of the cap.

Referring now to the drawing, the cap selected to illustrate the invention is shown in its preferred form, the jar being of glass. It will be understood, however, that as to 55 certain of its features the cap may be used with containers or jars other than glass jars, such for instance as porcelain or metal.

Referring to the construction illustrated, there is provided a glass jar 1 having an 60 open mouth, which is closed by a cap structure indicated generally by the numeral 2. This jar is provided with a locking shoulder in the form of a screw thread 3.

Cooperating with this jar is a cap which in 65 the particular construction illustrated is of two pieces only, the parts of this cap being of light metal and being formed by drawing the metal to the required shape. As illustrated, this cap includes a domed top 4 which terminates in a narrow flange 5, from which depends a skirt 6. This skirt is provided with a locking device which cooperates with the thread 3 of the jar mouth 1 and, as shown, this locking device is in the form of a screw 70 thread 7 produced by forming in the metal of the skirt 6 of the cap. This forming in of the metal to produce the thread 7 leaves outwardly showing corrugations or depressions 75 8. In accordance with the invention, means 80 are provided for concealing these corrugations.

While these means may be of various characters, in the particular construction illustrated there is provided an open ring 9 which 85 is substantially the dimension of the skirt 6 of the cap and is provided with a slightly inturned flange 10, which laps over onto the flange 5 of the cap, before referred to. Thus the ring conceals the depressions or corrugations 8 in a very simple and effective manner.

In accordance with the invention, means 90 are provided for rigidly locking the cap and ring together, and these means will be such as to be concealed when the two parts of the cap have been assembled. In the particular construction illustrated, this is effected by providing one or more locking tabs 11, two 95 such tabs being shown in Figure 3, although 100

it will be understood that under some circumstances one of these tabs may be omitted. These tabs are conveniently formed by providing a little excess metal on the flange of the ring, which is bent downwardly and inwardly so as to lie under the flange 10 and be concealed thereby. This tab, or tabs where more than one is used, is shaped to pass through slits 12 formed at the juncture 5 of the dome 4 of the cap and at the inner edge of the flange 5, and after the tab has been passed through the slot it may be bent upwardly under the shoulder 13, formed by the edge of the dome, and then flatwise 10 against the inside of the domed top 4, as indicated at 14 in Figure 4.

It will be seen that when the parts are assembled the flange 10 entirely conceals the slots 12 and also conceals the locking tab 20 or tabs, so that the cap when finished has the appearance of a one piece cap and at the same time conceals the locking means by which the cap is secured to the jar. This construction has the further advantage that 25 the cap proper may be finished in one way and the ring in another, where a contrasting cap is desired by the user.

It will be understood that the word jar as used in the specification and claims is intended to cover open mouthed containers of various characters adapted for the purpose of 30 the invention.

While the invention has been described in its preferred form, it will be understood 35 that certain changes and variations may be made in the specific structure of the locking device by which the cap is locked to the jar and by which the two parts are locked together without departing from the invention 40 as defined in the appended claims.

What I claim is:

1. A jar having a mouth and an exterior locking shoulder, a metal cap comprising 45 two parts only, one part providing a cover for the jar and having an outwardly extending peripheral flange and also having a skirt adapted for association with the jar and provided on its interior surface with co-operating locking devices produced by forming in the metal of the cap, the other part of the cap comprising an open ring enclosing 50 the skirt and concealing the same and having a concentric inwardly extending peripheral flange extending over the cover flange, and concealed means carried by the ring and bearing against the inside of the cover for rigidly locking the cap and ring together.

2. A jar having a mouth and an exterior locking shoulder, a metal cap comprising 60 two parts only, one part providing a cover for the jar and having an outwardly extending peripheral flange and also having a skirt adapted for association with the jar and provided on its interior surface with co-operating locking devices produced by forming in the metal 65

of the cap, a slit in the cap located in the cover flange, the other part of the cap comprising an open ring enclosing the skirt and concealing the same, an inwardly turned flange on the ring extending over the cover 70 flange, and a locking tongue on the ring flange entering the slit in the cap and bent in under the cap face and concealed by the flanges on the ring and cover.

In testimony whereof, I have hereunto set 75 my hand.

AUGUST MITCHELL.
